UNITED STATES PATENT OFFICE.

VIRGINIA ANN GALAGHER, OF NEWPORT, KENTUCKY.

DESIGN FOR A HOOK.

SPECIFICATION forming part of Design No. 34,534, dated May 21, 1901.

Application filed April 15, 1901. Serial No. 56,019. Term of patent 14 years.

To all whom it may concern:

Be it known that I, VIRGINIA ANN GALAGHER, a citizen of the United States, residing at Newport, in the county of Campbell and State of Kentucky, have invented and produced a new and original Design for a Hook, of which the following is a specification.

This invention relates to a new and original design for a curtain-hook, and the essential features reside in the design as illustrated in the accompanying drawings, wherein—

Figure 1 is a perspective view of a hook embodying the design. Fig. 2 is a side elevation of the same.

The design is characterized by a pair of approximately circular hooks 1, with outturned curved extremities 2, having pointed termi-

nals 3. The said hooks are precisely duplicate in their contour and arranged in parallel relation, the upper back portions 4 being outcurved reversely to the extremities 2, and from said portions 4 the parts of the hook adjacent converge and merge into a twisted shank 5, with a pointed terminal 6.

Having thus described the invention, what is claimed as new is—

The design for a hook, as herein shown and described.

In testimony that I claim the foregoing as my own I have hereto affixed my signature in the presence of two witnesses.

VIRGINIA ANN GALAGHER.
